UNITED STATES PATENT OFFICE.

PERCIVAL JAMES PACKMAN, OF LONDON, ENGLAND, ASSIGNOR OF ONE-HALF TO
WILLIAM MANNING, OF LONDON, ENGLAND.

MUSICAL INSTRUMENT OF THE REED TYPE.

Application filed June 27, 1927, Serial No. 201,914, and in Great Britain May 3, 1927.

This invention relates to musical instruments of the reed type, and more particularly to saxophones and has among its objects to provide for the operation of the octave key in such manner that risk of disturbing the embouchure when playing the higher notes of the instrument is avoided, to provide simplified key mechanism for certain of the higher note holes and generally to provide for the notes in the higher range of the instrument to be produced with greater ease and greater flexibility than is usual.

The octave key in saxophones and the like of known construction is operated by the thumb of the left hand and by reason of the disposition of certain of the keys of notes in the higher range certain intervals involving the use of the octave key can only be played with difficulty and with the possibility of disturbing the position of the reed and mouthpiece in the lips of the player. Thus, in an E_b alto saxophone this difficulty occurs in passing from C to D, E_b and F in the higher register.

According to the invention the fingering of these difficult intervals is greatly simplified by carrying the key mechanism of the octave key down the instrument to a position, where it may be operated by the thumb of the right hand, thus leaving free the left hand for the operation of the keys for the notes of the higher range with greater ease. A modified form of the key for operation by the thumb of the left hand may be provided to permit alternative operation of the octave hole pad from the left hand.

According to the invention, moreover, the keys of the note holes, which in an E_b alto saxophone correspond to the notes D and E_b , may conveniently be so arranged that they occupy the position left free by the omission of the usual octave key for operation by the left hand so that they may thus be operated by the thumb of the left hand.

Further, according to the invention, the pad of the note hole which in an E_b alto saxophone corresponds to the note $E^{\#}$ may be provided for alternative operation by the first finger of the left hand, or a duplicate hole with the pad so operated may be provided in the rearrangement of the adjacent note holes rendered possible by the omission of the usual octave key.

Similarly, the $F^{\#}$ key may be provided for operation by the first or second finger of the left hand.

It will be understood that the key mechanism for operating the octave key from the right hand may be provided in various ways, thus, the rotary sleeve or rod usually adopted may be extended downwardly to a point adjacent the thumb bracket by which the instrument is steadied upon the thumb of the right hand and the key may be disposed adjacent the said bracket for direct depression by the thumb, or a sleeve or rod extending downwardly as described, but in an adjacent position, may effect the operation of the mechanism through suitable coupling arms, or again the movement of a key adjacent the thumb bracket may be conveyed to the operating rods at the upper end of the instrument by a system of levers and links. To facilitate the operation of the key by the thumb it is advantageous that a pivoted ring or cradle should be provided for the thumb in addition to or instead of the bracket before referred to.

Similarly, the construction of the key mechanism for the notes of the higher range, the keys of which it is desired to dispose in the position left vacant by the omission of the octave key operated by the left hand, may be varied. Thus, the keys for the adjacent notes, for example, D and E_b in the E_b alto saxophone may be disposed side by side for operation by rolling movements of the thumb of the left hand, or they may be disposed one in advance of the other so that they may be operated by a forward and backward movement of the said thumb. It is desirable to provide a thumb rest adjacent the said keys and such thumb rest may be of a form partly surrounding or embracing the said keys.

The invention is applicable either to existing instruments or in the manufacture of new instruments. In the latter case it will be understood that the positions of the note holes of the upper range may be re-distributed around the periphery of the instrument in order to facilitate the arrangement of the operating keys and to secure the most simple form of mechanism for operation of the said keys by the thumb or first or second finger respectively of the left hand. Similarly, the mechanism for operating the octave key may also be varied in its position upon the instru-

ment for the purpose of facilitating the construction and operation of the mechanism.

It will be understood that by the re-arrangement of the keys according to the invention the difficulty in applying certain of the intervals in the higher range is overcome while the fingering generally is rendered simpler and made more flexible.

The invention is illustrated by way of example in the accompanying diagrammatic drawings.

Figure 1 represents a development of a portion of a saxophone to which one arrangement of mechanism in accordance with the invention has been applied.

Figure 1^a is a cross-sectional detail.

Figure 2 is a similar view showing a modified form of the mechanism controlling the octave key provided according to the invention.

Figure 3 is a similar view showing a further modification of the mechanism controlling the octave key provided according to the invention.

Figure 4 is a view illustrating the application of the invention to an existing instrument.

Figure 5 is a perspective view of a construction of thumb bracket for the thumb of the right hand.

Figure 6 is a view of a further form of the thumb bracket shown in Figure 5.

Referring to the accompanying diagrammatic drawings, and more especially to Figure 1, the particular pads which are concerned in the application of the invention are the pads 1, 2, 3, 4 and 5, which, in an E_b alto saxophone, for example, are respectively 1 the lower octave pad, 2 the pad for F[#], 3 the pad for E[#], 4 the pad for E_b and 5 the pad for D[#]; while the upper octave pad positioned upon the mouthpiece portion of the instrument is operated in the usual way by the ring 6. In existing instruments the ring 6 and the pad 1 are both released for operation, by a key 7, shown in dotted lines, provided for the thumb of the left hand, which is normally seated upon the thumb rest 9, while the pads 2, 4 and 5 are respectively operated by keys 10, 11 and 12, also shown in dotted lines.

In the application of the invention in the manner illustrated in Figure 1, the key 7 is removed and the arm 8 is extended laterally to engage an arm 13 fitted upon a sleeve portion 14, connected by a crank bar 15 to a longitudinally extending rod 16 carried into proximity with the right hand thumb bracket 31 adjacent which is disposed a thumb rest 32. At this point the rod 16 is provided with a key 17 for operation by the thumb of the right hand.

The omission of the key 7 leaves available space which may advantageously be occupied by keys serving for the operation of the pads

4 and 5, these keys, respectively 33 and 34, and the corresponding pads 4 and 5 being carried by sleeves 35, 36 positioned upon the rod 16 which passes through the sleeve 14.

An auxiliary key 18 is advantageously provided in a position lateral to the thumb rest 9, being provided with an arm secured to the rod 16 so that by the use of the key 18 the arm 18 may be operated also by the thumb of the left hand in the usual manner.

In view of the substitution of the keys 33, 34 for the usual keys 11, 12, the first and second fingers of the left hand may be employed for the operation of the keys corresponding to the pads 2 and 3. For this purpose the key 10 is removed and a key 37 provided in a suitable position in its stead, the pivotal point of the said key being carried relatively near to the pad 2. Similarly, a key 38 may be provided adjacent the key 37 for the operation of the pad 3, which for the purpose is provided with a lug 39 with which the end of the lever of the key 38 engages, the said lever or the lever of the pad 2 and key 37 being formed suitably to secure clearance. The key 37 may be operated by the first or the second fingers of the left hand, while the key 38 is adapted for operation by the first finger of the said hand.

Figure 2 shows a modified arrangement of the octave key mechanism in which, upon the removal of the key 7, a rod 19 in extension of the original rod of the key 7 is carried longitudinally along the instrument into a position adjacent the pad 37 above the thumb bracket 31, the rod being suitably cranked where necessary, as at 20, to clear the pad 40. In this construction the keys 17 and 18 are carried on arms which extend around the thumb rests 9 and 31. In this arrangement the sleeves 35, 36 for the pads 4 and 5 are mounted together and separately from the rod 19. By reason of the additional space which is rendered available the key 38 may be adapted to serve for the operation of the pad 41 for a note hole in duplication of that served by the pad 3, or the arrangement described with reference to Figure 1 may be adopted.

The arrangement of the mechanism according to the invention as illustrated in Figure 3 is substantially the same as that represented in Figure 2, with the exception that in place of the rod 19 a lever operating mechanism is provided comprising a key 21 pivoted in position adjacent the thumb rest 32, the lever 22 which is rocked about its pivotal point 23 by the key 21, a lever 24 rocked about the pivotal point 25 by the lever 22, and lever 26 pivoted at 27 and carrying the second key 28 which lever engages and depresses a lever 29 pivoted at 30, the lever 29 serving to depress the arm 8 of the octave mechanism.

Referring to Figure 4, which illustrates the

application of the invention to existing instruments, the octave controlling mechanism applied in accordance with the invention is similar to that illustrated in Figure 1, but in 5 addition to the removal of the key 7 it may be necessary to set the sleeve of the arm 8 at a slight angle to the axis of the instrument and to set the thumb rest 9 over laterally to a slight extent. The pads 4, 5 may, however, be 10 provided for alternate operation by the thumb of the left hand by means of keys 35, 36 provided with sleeves 33, 42 and adapted to engage respectively the lugs or spurs 43, 44 provided upon the pads 4 and 5. In this 15 adaptation, the pads 2 and 3 may be provided to be operated in the manner which is illustrated with respect either to Figures 1 or 2.

In view of the use which is made of the right thumb, in accordance with the invention, it is desirable that facility should be given for the movement of the thumb relatively to the instrument. For this purpose the thumb bracket 31 requires to be capable of movement to a limited degree, either of 25 rotation about a pivot normal to the axis of the instrument, or of universal movement about an axis normal to the axis of the instrument.

Figure 5 shows, in perspective view, a construction of thumb bracket giving a movement of rotation about a pivot that is normal to the axis of the instrument. In this construction the bracket 31 is provided with an open hook-like fitting for the base of the 35 thumb pivoted upon a support 45 fitted upon the wall of the instrument, the support 45 being provided with a surface upon which the bracket 31 may rotate.

In the construction represented in Figure 40 6, the bracket 31 is provided with a stem having a ball end adapted to be received into a cup seating formed in a supporting block 46 fitted on the wall of the instrument, the ball being maintained in position by a cover plate 45 47, advantageously in two parts, retained in position by screws or other suitable means. The supporting block 46 is provided with an extension 48, the outer face of which serves 50 as a bearing surface for the face of a spur 49 provided upon the bracket 31, which is adapted to limit the movement of the bracket in the upward direction under the weight of the instrument. The spur 49 may be provided with a bearing roller 50.

55 It will be understood that, whatever the form of octave key controlling mechanism adopted, any one or all of the several modifications in the key mechanism hereinbefore described may also be adopted, in any one of the several constructive forms.

It will further be understood that reference is made to the E_b alto saxophone merely by way of example and that the invention may be applied to all instruments of the type 60 and to other reed instruments.

I claim:

1. Musical instruments of the reed type, and more especially saxophones, provided with octave key mechanism and a key for controlling the said mechanism positioned adjacent to the position of, and for operation by, the thumb of the right hand of the player.

2. Musical instruments of the reed type, and more especially saxophones, provided with octave key mechanism, a rocking member 75 extending longitudinally of the instrument and operating the said mechanism, and a key controlling the said rocking member for operation by the thumb of the right hand of the player.

3. Musical instruments of the reed type, and more especially saxophones, provided with octave key mechanism, means for operating the said octave key mechanism, a thumb bracket for the thumb of the right hand, and a key controlling the said means and positioned adjacent the said thumb bracket, for operation by the thumb of the right hand of the player.

4. Musical instruments of the reed type, 90 and more especially saxophones, provided with octave key mechanism, a rocking member for operating the said mechanism, a second rocking member extending longitudinally of the instrument, coupling members carried by and connecting the said rocking members, and a key controlling the second rocking member for operation by the thumb of the right hand of the player.

5. Musical instruments of the reed type, 100 and more especially saxophones, provided with octave key mechanism, a rocking member operating the said mechanism, a series of levers extending longitudinally of the instrument and serving when moved to rock the said 105 rocking member, and a key controlling the movement of the series of levers for operation by the thumb of the right hand of the player.

6. Musical instruments of the reed type, 110 and more especially saxophones, provided with octave key mechanism, means for operating the said octave key mechanism, and keys for controlling the said means for operation respectively by the thumbs of the two hands of the player.

7. Musical instruments of the reed type, 120 and more especially saxophones, provided with octave key mechanism, means for operating the said octave key mechanism, thumb rests for the respective thumbs of the two hands of the player, and thumb keys positioned adjacent the said thumb rests and controlling the said means.

8. Musical instruments of the reed type, 125 and more especially saxophones, provided with octave key mechanism, means for operating the said octave key mechanism, thumb rests for the respective thumbs of the hands of the player, two thumb keys controlling the said means and respectively positioned adja- 130

cent the thumb rests, two additional thumb keys adjacent the thumb rest for the thumb of the left hand, and pads controlling note holes of the higher register, connected to, and controlled by, the said additional thumb keys.

9. Musical instruments of the reed type, and more especially saxophones, provided with octave key mechanism, means for operating the said octave key mechanism, thumb 10 rests for the respective thumbs of the hands of the player, two thumb keys respectively positioned adjacent the said thumb rests and controlling the said means, two finger keys disposed in correct relation to the thumb rest 15 for the thumb of the left hand for operation by the first and second fingers of the left hand, and pads controlling note holes of the higher register, connected to, and controlled by, the said finger keys.

10. Musical instruments of the reed type, and more especially saxophones, provided with octave key mechanism, means for operating the said octave key mechanism, thumb rests for the respective thumbs of the hands of 20 the player, two thumb keys positioned adjacent the said thumb rests and controlling the said means, two finger keys in correct relation to the thumb rest for the thumb of the left hand for operation by the first and second 25 fingers of the left hand, a pad controlling one of the note holes of the higher register connected to and controlled by one of the said finger keys, and a pad controlling the note hole which is a duplicate of one of the note 30 holes of the higher register, connected to, and controlled by, the second of the said finger keys.

11. Musical instruments of the reed type, and more especially saxophones, provided 40 with octave key mechanism, means for operating the said octave key mechanism, thumb rests for the respective thumbs of the hands of the player, two thumb keys controlling the said means and respectively positioned adjacent the thumb rests, two additional thumb 45 keys adjacent the thumb rest for the thumb of the left hand, pads controlling note holes of the higher register connected to, and controlled by, the said additional thumb keys, two finger keys disposed in correct relation to the thumb rest for the thumb of the left hand, for operation by the first and second fingers 50 of the left hand, and pads controlling note holes of the higher register connected to and controlled by the said finger keys.

12. Musical instruments of the reed type, and more especially saxophones, provided with octave key mechanism, means for operating the said octave key mechanism, thumb 60 rests for the respective thumbs of the hands of the player, two thumb keys controlling the said means and respectively positioned adjacent the thumb rests, two additional thumb keys adjacent the thumb rest for the thumb of the left hand, pads controlling note holes 65 of the left hand, pads controlling note holes

of the higher register connected to, and controlled by, the said additional thumb keys, two finger keys in correct relation to the thumb rest for the thumb of the left hand for operation by the first and second fingers of 70 the left hand, a pad controlling one of the note holes of the higher register connected to, and controlled by, one of the said finger keys, and a pad controlling a note hole which is a duplicate of one of the note holes of the higher register, connected to, and controlled by, the second of the said finger keys.

13. Musical instruments of the reed type, and more especially saxophones, provided with key mechanism, means for operating the said octave key mechanism, thumb rests for the respective thumbs of the hands of the player, two thumb keys controlling the said means and respectively positioned adjacent the thumb rests, two additional thumb keys 80 adjacent the thumb rest for the thumb of the left hand, two pads controlling note holes of the higher register, and coupling members between the said pads and said additional thumb keys for operation of the pads therefrom.

14. Musical instruments of the reed type, and more especially saxophones, provided with key mechanism, means for operating the said octave key mechanism, thumb rests for the respective thumbs of the hands of the player, two thumb keys controlling the said means and respectively positioned adjacent the thumb rests, two additional thumb keys adjacent the thumb rest for the thumb of the left hand, two pads controlling note holes of the higher register, coupling members between the said pads and said additional thumb keys for operation of the pads therefrom, two finger keys disposed in correct relation to the thumb rest for the thumb of the left hand, for operation by the first and second fingers of the left hand, and pads controlling note holes of the higher register connected to and controlled by the said finger keys.

15. Musical instruments of the reed type, and more especially saxophones, provided with key mechanism, means for operating the said octave key mechanism, thumb rests for the respective thumbs of the hands of the player, two thumb keys controlling the said means and respectively positioned adjacent the thumb rests, two additional thumb keys adjacent the thumb rest for the thumb of the left hand, two pads controlling note holes of the higher register, coupling members between the said pads and said additional thumb keys for operation of the pads therefrom, two finger keys in correct relation to the thumb rest for the thumb of the left hand for operation by the first and second fingers of the left hand, a pad controlling one of the note holes of the higher register connected to, and controlled by, one of the said finger keys, and a pad controlling a note hole which is a 125 130

duplicate of one of the note holes of the higher register, connected to, and controlled by, the second of the said finger keys.

16. Musical instruments of the reed type, and more especially saxophones, provided with octave key mechanism, means for operating the said octave key mechanism, thumb rests for the respective thumbs of the two hands of the player, thumb keys positioned adjacent the thumb rests and controlling the said means, and a bracket for the thumb of the right hand, the said bracket being mounted for universal movement about an axis normal to the axis of the instrument. 25
- 10 adjacent the thumb rests and controlling the said means, and a bracket for the thumb of the right hand, the said bracket having a limited movement of rotation on an axis normal to the axis of the instrument.
- 15 17. Musical instruments of the reed type, and more especially saxophones, provided with octave key mechanism, means for operating the said octave key mechanism, thumb rests for the respective thumbs of the two hands of the player, thumb keys positioned 30
- 20 adjacent the thumb rests and controlling the said means, and a bracket for the thumb of the right hand the said bracket being mounted for universal movement about an axis normal to the axis of the instrument, and provided with means to limit the movement of the bracket under the weight of the instrument. 35

adjacent the thumb rests and controlling the said means, and a bracket for the thumb of the right hand, the said bracket being mounted for universal movement about an axis normal to the axis of the instrument. 25

18. Musical instruments of the reed type, and more especially saxophones, provided with octave key mechanism, means for operating the said octave key mechanism, thumb rests for the respective thumbs of the two hands of the player, thumb keys positioned adjacent the thumb rests and controlling the said means, and a bracket for the thumb of the right hand the said bracket being mounted for universal movement about an axis normal to the axis of the instrument, and provided with means to limit the movement of the bracket under the weight of the instrument. 30

PERCIVAL JAMES PACKMAN.
